UNITED STATES PATENT OFFICE.

EDGAR KLING, OF LOUISVILLE, KENTUCKY, ASSIGNOR TO ISAAC KLING, OF SAME PLACE.

CAR-COUPING.

SPECIFICATION forming part of Letters Patent No. 501,428, dated July 11, 1893.

Application filed April 3, 1893. Serial No. 468,866. (No model.)

To all whom it may concern:

Be it known that I, EDGAR KLING, of Louisville, in the county of Jefferson and State of Kentucky, have invented certain new and useful Improvements in Car-Couplings; and I do hereby declare that the following is a full, clear, and exact description thereof, reference being had to the accompanying drawings, and to the letters of reference marked thereon, which form part of this specification.

The invention relates to car couplings and is an improvement upon the coupling shown in the patent granted to me on the 19th day of July, 1892, No. 479,371; and its object is to provide an efficient, accurate and simple coupling, and to provide improved uncoupling devices, and to prevent falling of the draw bar should it break from its fastenings.

The invention therefore consists in the novel construction of the draw bar, jaw, locking pin, and uncoupling rod and bracket substantially as hereinafter described and claimed.

Referring to the drawings by letter:—Figure 1 is a front perspective view of a twin jaw coupling embodying my improvements. Fig. 2 is a detail enlarged transverse sectional view on line 2—2 Fig. 1. Fig. 3 is a horizontal sectional view on line 3—3 Fig. 2. Fig. 4 is a detail tail.

The draw bar A resembles an ordinary twin jaw coupling draw bar. If desired its ears *a*, *a*, may be extended farther forward than usual, and curved as shown so as to form a part of the "knuckle" or locking portion of the coupler, and enable the locking arm *b* of the jaw to be made shorter than usual thereby enabling a coupling to be made on a much sharper curve than where the locking arms of the jaws are long, because the pivot pin of the jaw is of course farther forward, or in front of the mouth of draw bar.

The jaw B resembles an ordinary locking jaw having locking arm *b* and a bevel or incline *b*⁴ is formed at the junction of the arm and shank *b*' as shown and hereinafter referred to, and the inner end of the shank is beveled as at *b*² for a purpose hereinafter described.

The coupling pin C has its upper part *C*³ angular in cross section (preferably square)

so that the pin cannot revolve in the openings. The lower portion *c* of the pin is so cut away as to leave it triangular in section, a shoulder *c*' being formed at the junction of the triangular and square portions of the pin. An elongated vertical slot *C*' is made in the upper part and transversely of the pin through which slot passes freely a curved lever D one end of which is pivoted between lugs or ears *a*' on top of the draw bar at one side of the pin opening.

A pull rod E is loosely connected to lever D near its pivoted end and extends to one side of the car passing through a retainer or guide loop *f* on a bracket F attached to the car as indicated. The pull rod is bent upon itself and formed into a hand hold E' outside the loop which prevents the rod pulling through the guide so that should the coupling with which the rod is connected become detached, or be drawn out unusually far, the pull rod cannot slip through the guide loop and will raise the pin, as by pulling on the rod E, lever D is swung to a substantially upright position and lifts the pin as indicated in Fig. 2. The outer end E³ of lever E extends back through the loop when the lever D is lowered and the pin in position to lock the jaw, but when the rod is fully drawn out so as to lift lever D as shown in Fig. 2, the end E³ catches against loop *f* and holds the lever D raised and permits the coupling pin from dropping, which it is sometimes desirable to do when shifting cars on side tracks. The pivoted end of lever D is shouldered at *d* to form a stop which limits its swinging movement by striking against the draw bar. The bevel *b*² on the end of shank *b* of the swinging jaw when the shank swings inward, catches beneath shoulder *c*' of the pin and rides the latter upward, thus raising the pin until the shank passes when it drops by gravity and thereby locks the jaw as is evident. The slot *C*' being long allows the pin to be thus lifted without disturbing lever D; thus the coupling can be effected automatically. The uncoupling is effected by pulling rod E thereby raising the lever D and pin as above stated.

The shank *b*' has a projection or shoulder *b*³ on its rear edge, which (when the jaw is in locked position) engages a corresponding re-

cess a^3 in the side of draw bar, and thereby can partly relieve the pivot pin of the jaw from draft strain.

An abutment a^4 is formed in the throat of the draw bar extending from bottom to top thereof at the side of the pin opposite the end of the shank when the latter is locked as shown in Fig. 2. This abutment is to relieve the pin of strain, by transferring the lateral pressure from the shank direct through the pin to the side of draw bar, so that the pin will not be bent.

A bevel or incline a^6 is made at the junction of the lower ear a with the body of draw bar, this bevel extending from the top of ear upwardly to the top of the floor of draw bar, and it is engaged by the oppositely beveled or rounded portion b^4 of the jaw. The bevels are so located that as the jaw closes it will be raised by the opposition of said bevels, and will swing open by gravity into coupling position when released.

G designates a chain which is fastened to one side of the draw bar, at one end, and to the car at its other end. This chain in conjunction with rod E constitutes a safety device for suspending the draw bar in case it should be broken loose from its fastenings. Should the draw bar be broken loose and pulled out of its supports, the rod E being limited in its movement by hand hold E' will raise lever D and uncouple the hook, and then in conjunction with chain G will suspend the bar above the track, and thus prevent the danger incident to the falling of a draw bar on the track.

The rod E may be attached to top or side of the car. Two or more rods may be used to operate the same lever D .

Having thus described my invention, what I claim as new, and desire to secure by Letters Patent thereon, is—

1. The combination of the draw bar and coupling pin with a lever pivoted at one end on the draw bar and loosely connected to the pin and adapted to lift the pin when turned upward on its pivot, substantially as and for the purpose specified.

2. The combination of the draw bar and pin, with a curved lever pivoted at one end on draw bar and slidably engaging the pin at its other end, and a pull rod for swinging said lever upward, substantially as described.

3. The combination with the draw bar and a locking pin having an elongated slot in its upper end, of a lever playing through said slot and pivotally connected at one end to said draw bar, substantially as described.

4. The combination with the draw bar and swinging jaw of a locking pin adapted to be automatically raised by the arm of said jaw when the jaw closes having an elongated slot in its upper end, and a lever playing through said slot and pivotally connected at one end to said draw bar, substantially as described.

5. The combination of the draw bar, the

vertically movable pin, the lever playing through a slot in the pin, and a pull rod E loosely connected to one end of the bar, and having a hand hold E' , all constructed and arranged to operate substantially as described. 70

6. The combination of the draw bar having pin openings and an abutment at one side between the pin openings, and a swinging jaw with the locking pin adapted to bear laterally against said abutment, substantially as described. 75

7. The combination of the draw bar, the pin and the pivoted lever D having shoulder d , substantially as specified. 80

8. The combination of the draw bar, the swinging jaw having a bevel adapted to engage an opposite bevel on the draw bar and lift the jaw when closing, and also beveled on the inner end of its arm; with the angular 85 pin shouldered and slotted as described, the pivoted lever passing through the slot of the pin, and the pull rod connected to said lever all constructed and arranged to operate substantially as described. 90

9. The combination of the draw bar having forwardly curved ears, pin openings, and an interior abutment at one side; with the locking pin, and the swinging jaw pivoted between said ears, substantially as described. 95

10. The combination of the draw bar having forwardly curved ears, pin openings and an interior abutment; with the pin, the swinging jaw pivoted between said ears, the coacting opposed bevels on the jaw and draw bar, and a pivoted lever and pull rod for lifting the pin, substantially as and for the purpose described. 100

11. The combination of the draw bar and uncoupling lever pivoted thereon, with the 105 guide loop f , the pull rod E pivotally connected to said lever and extending through said loop, and having a hand hold and catch, substantially as and for the purpose described.

12. The combination of the draw bar the 110 uncoupling lever pivoted thereon, and the pull rod passing through a guide loop on the car pivotally connected to said lever, and having a hand hold on its outer end; with the chain G , all constructed and arranged to 115 operate substantially as and for the purpose set forth.

13. The combination of the draw bar, the vertically movable pin, the lever playing through a slot in the pin, and the pull rod E 120 loosely connected to one end of the bar and having a hand hold E' , and the loop f , and the chain G , all constructed and arranged to operate substantially as and for the purpose described. 125

In testimony that I claim the foregoing as my own I affix my signature in presence of two witnesses.
